UNITED STATES PATENT OFFICE.

CHARLES F. SMITH, OF NEW BRITAIN, CONNECTICUT, ASSIGNOR TO LANDERS, FRARY & CLARK, OF NEW BRITAIN, CONNECTICUT, A CORPORATION OF CONNECTICUT.

DESIGN FOR A STAND FOR HEATED UTENSILS.

45,970.

Specification for Design.

Patented June 16, 1914.

Application filed April 29, 1913. Serial No. 764,448. Term of patent 14 years.

To all whom it may concern:

Be it known that I, CHARLES F. SMITH, a citizen of the United States, and a resident of New Britain, in the county of Hartford, State of Connecticut, have invented a new, original, and ornamental Design for a Stand for Heated Utensils, of which the following is a specification, reference being had to the accompanying drawing, forming part hereof.

Figure 1 is a plan view of a stand made

in accordance with my invention. Fig. 2 is a side elevation thereof. Fig. 3 is an end elevation thereof.

I claim:

The ornamental design for a stand for heated utensils, as shown.

CHARLES F. SMITH.
